DESIGN FOR A FISH LURE

Le Roy O. Edwards, East Hampton, N. Y.

Application October 6, 1933. Serial No. 49,413

Term of patent 14 years

To whom it may concern:

Be it known that I, LE ROY O. EDWARDS, a citizen of the United States, residing at East Hampton, in the county of Suffolk and State of New York, have invented a new, original, and ornamental Design for a Fish Lure, of which the following is a specification, reference being had to the accompanying drawing, forming part thereof, in which

I claim:

The ornamental design for a fish lure, as shown.

LE ROY O. EDWARDS.
